UNITED STATES PATENT OFFICE.

ROBERT A. MONTGOMERY, OF INDIANA, PENNSYLVANIA.

WRENCH.

961,515.

Specification of Letters Patent. Patented June 14, 1910.

Application filed April 17, 1909. Serial No. 490,476.

To all whom it may concern:

Be it known that I, ROBERT A. MONTGOMERY, a subject of the King of Great Britain, and a resident of Indiana, in the county of Indiana and State of Pennsylvania, have invented a new and Improved Wrench, of which the following is a full, clear, and exact description.

The invention is an improvement in internal wrenches, more especially for radiator valves, and has in view a tool presenting a number of such wrenches of varying size, each wrench being stepped from the adjoining wrench, and the several wrenches decreasing in size toward the inner end or point of the tool, the outer edges of the wrenches preferably, though not necessarily, presenting cutting edges, adapting the tool to be also used as a reamer.

Reference is to be had to the accompanying drawings forming a part of this specification, in which similar characters of reference indicate corresponding parts in all the views.

Figure 1 is a side view of the tool partly in central vertical section; Fig. 2 is an inner end view of the tool; and Fig. 3 is a cross-section of the tool on the line 3—3 of Fig. 1, on an enlarged scale.

The body of the tool is composed of a number of blades 5 radiating from a common central stem to which they are integrally formed or otherwise rigidly connected throughout their length, four of these blades being shown arranged ninety degrees apart, thus disposing each set of blades at diametrically opposite points. Each blade tapers from the center of the tool outwardly, with the thickest portion of each blade arranged adjacent to the central stem of the tool. Each blade has a stepped outer cutting edge, with the widest portion of the blade at the top and the successive portions of the cutting edge approximately parallel to the longitudinal axis of the tool. This construction of the blades produces a number of pipe reamers and internal wrenches successively increasing in size from the outer end of the tool toward the inner end thereof.

The shoulders 6 formed at the edges of the several blades, preferably incline inwardly toward the point of the tool in order that a bur may be easily cut from the end of a pipe in inserting the next larger portion of the reamer. At the inner and enlarged

portion of the body of the tool a shank is either integrally or separately attached and consists of a square or other angular wrench-engaging portion 7 adjacent to the tool body, and a reduced extremity 8 having in its end 60 a socket wrench 9. At diametrically opposite points the wrench-engaging portion 7 of the shank is provided with threaded recesses 10, which serve to attach handles, as indicated in dotted outline in Fig. 1, in operating the tool, or the handles may be dispensed with and a wrench applied directly to the angular portion 7 in using the tool as either a reamer or wrench.

A disk 10^a at the junction of the shank 70 and tool body reinforces the connection between these parts and rests on the top of the blades, to which it is rigidly joined, thus effectively tying the blades together and tending to prevent the same from being 75 broken out.

The tool is especially useful in steam fitting, in which work, as a wrench the tool is passed into the tail-piece of radiator valves of various sizes and the blades brought to 80 bear on the internal projections provided in connection with these pipe fittings, when the fitting is screwed on or off the radiator connections. The tool as a reamer is especially useful for cutting the burs from the ends 85 of various size pipes, after which the next larger portion of the tool is easily inserted.

Having thus described my invention, I claim as new and desire to secure by Letters Patent:

1. A tool comprising a central stem having blades radiating therefrom, the blades having stepped outer cutting edges forming a number of wrenches successively increasing in size from the outer end of the tool toward 95 the inner end or shank of the tool, with each wrench of approximately uniform diameter throughout its length.

2. A tool comprising a central stem having blades radiating therefrom and rigid 100 with the stem substantially their full length, the blades successively decreasing in width from the inner to the outer end of the tool and forming a succession of internal wrenches, said stem being extended beyond 105 the inner end of the blades to provide a shank and having a reinforcing disk rigid therewith and with the inner ends of the blades.

3. A tool having blades radiating from a 110

common longitudinal axis, the blades tapering in cross-section, with the thickest portion of each blade arranged adjacent to said axis, said blades having stepped outer edges forming a succession of internal wrenches successively increasing in size from the outer end of the tool inwardly.

In testimony whereof I have signed my name to this specification in the presence of two subscribing witnesses.

ROBERT A. MONTGOMERY.
